OF NEW YORK, N. Y., A CORPORATION OF NEW YORK.

COMBINATION-GARMENT.

1,109,015.

Specification of Letters Patent. Patented Sept. 1, 1914.

Application filed March 10, 1914. Serial No. 823,711.

To all whom it may concern:

Be it known that I, MAX PHILLIPS, a citizen of the United States, residing in the borough of Manhattan, city, county, and State of New York, have invented certain new and useful Improvements in Combination-Garments; and I do hereby declare the following to be a full, clear, and exact description of the invention, such as will enable others skilled in the art to which it appertains to make and use the same.

My invention relates to certain new and useful improvements in combination garments, and is particularly, although not exclusively intended for underwear, inasmuch as it is likewise applicable to use for other purposes, as, for instance, in the manufacture of pajamas, track suits, gymnasium wear, or the like.

20 In the accompanying drawing, Figure 1 represents a front view of a combination garment embodying my invention; Fig. 2 represents a rear view thereof.

Similar letters of reference indicate 25 similar parts in both views.

For purposes of illustration, I have shown the garment as sleeveless, although it will be understood that this is not of the essence of the invention, inasmuch as the garment may 30 be provided with the usual sleeves.

The rear of the garment, as shown in Fig. 2, is made of the necessary fullness, represented, for instance, by the gores a extending from the waist-line b, and has a closed 35 seat and a closed crotch c; so that, seen from the rear, it is appropriate to be worn even in public view. The legs d are intended to be, as indicated, of a length terminating above the knee of the wearer. The front of 40 the garment is closed by fastenings such as the buttons and button-holes e, which extend across one of the shoulders f and thence downward in a general longitudinal direction across the chest and abdomen and along 45 the front or upper portion of the leg, that is, forward of the crotch portion of the leg so as to be away from the crotch seam of the garment and within easy access of the wearer, thereby permitting him to readily 50 fasten and unfasten the garment, without putting himself in an unnatural position.

In Fig. 1, I have shown the garment as partially broken away along the irregular line n so as to more clearly illustrate the location of the edge portion h to which the buttons are attached,—it being understood that the overlying edge m is provided with the corresponding button-holes.

One of the advantages of the garment is that inasmuch as it opens down the shoulder, 60 it permits the wearer to slip into it more readily when unfastened than if fastened down the median line of the body. Furthermore, it permits the front panel or face s of the shirt to be carried over the chest, 65 without having an opening in the front of the neck; and it is more completely closed in the neighborhood of the crotch for the reason that the line of fastenings extends across the garment well above the location 70 of the crotch portion. The construction also permits the garment to be closed in the back as well as in the crotch, with the advantages incident thereto.

Having thus described my invention what 75 I claim is:

1. A combination garment provided with a front opening having a row of releasable fastenings, said opening extending laterally from the neck opening to a point adjacent 80 to the arm-hole on one side and then diagonally across the front of the body and along the leg on the other side, forward of the crotch portion of that leg; substantially as described.

2. A combination garment provided with a front opening having a row of releasable fastenings, said opening extending laterally from the neck opening to a point adjacent to the arm-hole on one side and then in a 90 substantially straight line diagonally across the body and along the leg on the other side forward of the crotch portion of that leg, said garment having a closed seat and closed crotch; substantially as described.

95 In testimony whereof I affix my signature, in presence of two witnesses.

MAX PHILLIPS.
